UNITED STATES PATENT OFFICE.

JOHN A. BAKER, OF GALVESTON, TEXAS.

ELECTRIC SIGNALING DEVICE.

No. 863,252.

Specification of Letters Patent.

Patented Aug. 13, 1907.

Application filed November 30, 1906. Serial No. 345,762.

To all whom it may concern:

Be it known that I, JOHN A. BAKER, a citizen of the United States, residing at Galveston, in the county of Galveston and State of Texas, have invented certain new and useful Improvements in Electric Signaling Devices, of which the following is a specification.

My invention relates to electric signaling devices and has for its object the provision of an improved device of this character, comprising a shelf and means carried by said shelf, which when the shelf is lowered to enable a watchman, telegraph operator or other person, to enter a record or report upon a paper pad carried by said shelf, completes an electric circuit to thereby actuate a signal at a distant station.

15 Further objects and advantages of the invention will be set forth in the detailed description which now follows.

In the accompanying drawing: Figure 1 is a front elevation of the device showing the shelf in an elevated position, Fig. 2 is a vertical section of the parts shown in Fig. 1, Fig. 3 is a like view with the shelf in its lowered position, and, Fig. 4 is a like view looking from the opposite side of the shelf.

Like numerals designate corresponding parts in all 25 of the figures of the drawing.

Referring to the drawing, the numeral 5 designates a wall or other support. Secured to this wall is a casing 6, the front of which is slotted as at 7 and 8. An insulating block 9 is secured to the inner wall of this casing and 30 carries a contact spring 10. The lower end of this contact spring is provided with a V-shaped projection 11 which is adapted to engage with teeth 12 which are formed upon a rearward extension 13 of a hinge plate 14, said hinge plate being pivoted as at 15 to an ear 16, 35 which is carried by the front of the casing. This hinge plate, together with a second hinge plate 17, supports a shelf 18. A pad of paper 19 is located upon this shelf and is secured thereto in any desired manner. The hinge plate 17 has a rearwardly extending portion 20 40 which is adapted to contact with a stop plate 21 to limit the downward movement of the shelf.

In Fig. 2, I have shown a wire 22 leading from the spring plate 10 to one of the poles of an electric bell 24 and I have shown a second wire 25 leading from the 45 hinge plate 14 to a battery 26. A third wire 27 leads from said battery to the other pole of the bell.

The operation of the device will now be described. In many large manufacturing establishments which cover a considerable area, watchmen are stationed at 50 different points about the buildings and are required to send in a report to the central office at given intervals. They are also required to make a written report at said intervals. The pad 19 serves to receive this written report and when the watchman pulls the shelf down to

the position illustrated in Fig. 4, to write upon the pad 55 19, the teeth 12 ride over the V-shaped end 11 of the spring 10 and complete the circuit to the bell 24. The number of these teeth may be varied, to give a distinctive signal, which will indicate at the central office the location of the person who is sending the signal. 60

The form of the device illustrated in Fig. 2 may be used when an audible signal is desired at the central station, but if it be desired to produce a permanent record at the central station, or at the office of a manufacturing establishment, the devices illustrated in Fig. 65 4 may be employed. In this instance, the wires 27 and 22 are connected to electro-magnets such as are used to ring an ordinary electric bell and having a vibratory armature 28. To this armature a pencil 29 may be secured which will mark a permanent record upon a sheet 70 30 which is carried by a revolving disk 31, said disk being driven by a clock mechanism, not shown, and contained in the casing 32. With this form of the device a record will be made upon this disk, say, every hour and it will indicate in the morning whether the watch- 75 man has been sending in his reports at proper intervals during the night.

This device may also be used by telegraph operators to receive instructions concerning certain trains. When the shelf is drawn down to record these instructions, a 80 signal such as 24 will be actuated in the main office from which the instructions were sent.

From the foregoing description, it will be seen that simple and efficient means are herein provided for accomplishing the objects of the invention, but while the 85 elements shown and described are well adapted to serve the purposes for which they are intended, it is to be understood that the invention is not limited to the precise construction set forth, but includes within its purview such changes as may be made within the scope of 90 the appended claims.

What I claim, is:

In a device of the character described, a casing having parallel slots in its front wall, a shelf pivoted to said casing adjacent said slots, said shelf having a rearward extension working in one of said slots, a fixed stop within said casing for engagement with said extension, said shelf also having a toothed rearwardly extended sector working in the other of said slots, a spring contact finger in said casing for engagement with said sector, a source of electrical supply, connections between said source of supply and said sector and between said source of supply and said spring contact finger, and an electric signaling device included in said connections. 95 100

In testimony whereof I affix my signature in presence of 105 two witnesses.

JOHN A. BAKER.
